UNITED STATES PATENT OFFICE.

DANIEL W. GOLDSMITH, OF CAMPBELL, MISSOURI.

POULTRY-NEST.

1,359,052.

Specification of Letters Patent. Patented Nov. 16, 1920.

Application filed February 12, 1920. Serial No. 358,068.

To all whom it may concern:

Be it known that I, DANIEL W. GOLDSMITH, a citizen of the United States, residing at Campbell, in the county of Dunklin 5 and State of Missouri, have invented certain new and useful Improvements in Poultry-Nests, of which the following is a specification.

This invention relates to improvements in 10 combination hens nest and brooder, and has for its object to provide an automatic nest for the protection of the hen while laying or setting. And further to provide an automatic nest for weeding out non-producing 15 from the producing fowl, and determining the hen which laid the specific eggs, and for indicating when the hen is on the nest. And further to provide an automatic nest which may be used for a summer brooder.

20 The invention consists of the novel construction and arrangement of parts herein-after more fully set forth in the following specification and pointed out in detail in the appended claims.

25 In the accompanying drawing:—

Figure 1 is a side elevation of my invention with the parts in the normal position.

Fig. 2 is a section on the line 2—2 of Fig. 1.

30 Fig. 3 is an end view showing the door in the lowered or open position.

Fig. 4 is a vertical section on the line 3—3 of Fig. 2.

Fig. 5 is a detail section showing the 35 spring for locking the entrance door in the open position.

Referring to the accompanying drawing forming, part of this specification, and in which like reference numerals designate like 40 parts throughout the several views thereof, 1 designates a casing having openings 2 in the side and ends, which said openings may be of any desired size, and the said casing 1 may be constructed of wood, metal or other 45 suitable material. In one side of the said casing near one end thereof is an opening 3 provided with a vertically slideable door 4, said door being connected by an arm 5 to the nest 6 by means of the pin 7 passing

50 through the aperture 8 in the side of the casing 1, said arm 5 being pivoted at 9 to the outer surface of the said casing 1. The nest 6 is provided with a platform 10 at one end, adjacent the opening 3, and is pivoted at 55 11 to the inner surface of the casing 1. A latch 12 is pivoted to the outer surface of the

casing 1 at 13 and has a notch 14 in one side adapted to take over the pin 7 to hold the door 4 in the closed position, the said latch 12 being held normally against the pin 7 60 by a spring 15. A hook 16 is also pivoted to the outer surface of the casing 1 and is adapted to fit over the upper end of the latch 12 to hold it out of engagement with the pin 7, as shown in dotted lines in Fig. 1. A 65 spring wire catch 17 has one end secured to the side of the casing 1 and its upper end projecting back of the wire piece 18 which is also secured to the side of the casing 1. This catch 17 projects over the arm 5 and 70 locks the door in the open position when the catch 17 is at the outer end of the wire 18, and when forced back into the wire 18 will release the arm 5 and allow the door 4 to be raised and lowered. When the hen enters 75 the opening 3 she will step upon the platform 10 and then down into the nest 6 causing the latter to tilt on the pivots 11 which results in the arm 5 being tilted on the pivot 9 and the door 4 raised closing the opening 80 3, in which position it is locked by the latch 12 engaging the pin 7. One end of the nest 6 is provided with a brush 19 which engages the brush 20 on the inner surface of the casing 1 for an instant as the nest is tilted 85 causing the bell 21 to ring. The said brushes 19 and 20 are connected by the wire 22 to the battery 23. In the end of the casing 1 back of the nest 6 is a door 24 which may be opened to allow the hen to pass out of the 90 nest when the door at the side is closed or locked. Just back of the door 24 is a rod 25 having one end hinged at 26 and its opposite end projecting into a groove 27. The end of the rod 25 which projects into the 95 groove 27 is provided with a cord or belt 28 which passes over the pulleys 29 and 30 and has its opposite end secured to the upper end of the latch 12 so that when the hen steps on said rod 25 its weight will cause the 100 said rod to be forced down and the latch 12 to release the pin 7, thereby allowing the arm 5 to tilt on the pivot 9 and the door 4 to drop away from the opening 3. The end of the nest 6 is provided with an upwardly 105 projecting piece 31 to prevent the hens from entering through door 24 when the nest is in the normal position.

When the device is to be used as a brooder the door 24 is kept closed and when the hen 110 enters through the opening 3 to the nest 6 the said opening 3 will be closed, as hereto-

fore described, and the door 4 locked over the said opening.

It will be seen that by having the door 24 at the rear the hens enter the opening 3 and 5 after laying pass out through the door 24 and as they do so again open the door 4 allowing another hen to enter through the opening 3 to the nest. The hens passing through the door 24 may enter another yard 10 or coop, thus separating the productive from the non-productive hens.

Alterations in the construction and arrangement of the parts may be made within the scope of the appended claims without 15 departing from the spirit of my present invention.

Having thus described my invention, what I claim is:—

1. A combined hens nest, and brooder, 20 comprising a casing having an opening in the side thereof near one end and a opening in one end thereof, a door slidable over the said side opening, a nest pivoted within said casing, an arm connecting the rear end 25 of said nest with the said door, a latch piv-

oted to the said casing and adapted to co-operate with the said arm to hold the door in the closed position, a rod near the lower end of the end opening of said casing, and means connecting the said rod and latch for 30 releasing the latter to allow the side door to be lowered.

2. A combined hens nest, and brooder, comprising a casing having an opening in one side near the one end thereof and an 35 opening in one end, a door slidable over said side opening, an arm pivoted to the side of said casing and connected to the said side door and nest, a latch co-operating with the said arm to hold the door in the closed position, a spring to hold the said latch normally against said arm, a rod extending across the said end opening, means connecting the said rod and latch for disconnecting the said latch and arm to allow the side door to be 40 opened, and means to lock the said side door in the open position.

In testimony whereof I affix my signature.

DANIEL W. GOLDSMITH.
